UNITED STATES PATENT OFFICE.

JOHN K. STEWART, OF CHICAGO, ILLINOIS; PHILIP C. LINDGREN, ADMINISTRATOR OF
SAID JOHN K. STEWART, DECEASED.

DIE-CASTING MACHINE.

1,231,808.

Specification of Letters Patent. Patented July 3, 1917.

Application filed January 5, 1916. Serial No. 70,379.

To all whom it may concern:

Be it known that I, JOHN K. STEWART, a citizen of the United States, residing at Chicago, in the county of Cook and State of Illinois, have invented new and useful Improvements in Die-Casting Machines, of which the following is a specification, reference being had to the accompanying drawings, forming a part thereof.

10 It is the purpose of this invention to provide a die casting machine in which the majority of operations are automatic and are mechanically timed with relation to one another, whereby the process as a whole may 15 be performed at considerably greater speed than is now possible. The invention consists in the features and elements of the machine and their combinations hereinafter described and shown in the drawings as indicated by the claims:

In the drawings:

Figure 1 is a side elevation of a die casting machine embodying this invention.

Fig. 2 is a top plan view of the same, 25 with certain parts broken away to reveal details of construction.

Fig. 3 is an enlarged detail section taken substantially as indicated at line 3—3 on Fig. 2.

30 Fig. 4 is a detail plan section taken principally as indicated at 4—4 on Fig. 1.

Fig. 5 is a detail section taken as indicated at line 5—5 on Fig. 3.

Fig. 6 is a detail section taken as indicated 35 at line 6—6 on Fig. 3.

Fig. 7 is a detail section taken as indicated at line 7—7 on Fig. 3.

Fig. 8 is a detail section taken as indicated at line 8—8 on Fig. 3.

40 Fig. 9 is a plan view of a melting pot and rotary table constructed to embody a modification of the means for moving the melting pot as well as certain other features not shown in previous figures.

Fig. 10 is a detail section taken as indicated 45 at line 10, 10, on Fig. 9.

Fig. 11 is a detail plan view of the gearing for actuating the brush shown in Fig. 10.

Fig. 12 is a detail elevation of a modified 50 valve controlling mechanism.

The machine illustrated in the drawings comprises the combination of a single melting pot, 1, with a plurality of dies or molds, 2, mounted upon a rotary carrier, 3, so as

to be successively registered and connected with the discharge nozzle, 4, of the melting pot, 1, to be filled with molten metal. The melting pot, 1, is very similar in construction and operation to that which is more fully described in my co-pending application Serial No. 62524, filed November 20th, 1915. The dies, 2, may be of the usual construction comprising an upper and a lower half, 2^a and 2^b, respectively, each provided with a sub-block, 2^c, having suitably arranged conduits for cooling water for cooling the casting. The rotary carrier, 3, includes a head plate, 5, connected to the table portion, 3, by upright guide rods, 6, which also serve as guides for the cross heads, 7, upon which the upper portions, 2^a, of the dies, 2, are carried. This assembly is rotatively mounted upon a stationary post or column, 8, as quite clearly indicated in Fig. 3.

It should be understood that the rotary carrier, 3, is intermittently rotated through a given angle and held at rest for a given time for successively filling the several dies or molds, 2, at the single nozzle, 4, of the melting pot, 1. The power for effecting this intermittent motion of the rotary carrier is transmitted through a constantly rotating power shaft, 9, having a worm, 10, meshing with a worm wheel or gear, 11, journaled to rotate about the post, 8, on which the die carrier is also rotatably mounted. The intermittent motion of the rotary carrier is accomplished by gearing involving the so-called Geneva stop principle, and consisting of three gears, 12, 13 and 14, all meshing with a single pinion, 15, as indicated in Fig. 3. The gear, 14, is a complete spur gear and is operatively connected for rotation with the table, 3, by pins, 16, engaging the pedestal, 3^a, of said table. Since in the particular machine shown there are four dies carried on the table, 3, each rotative movement of the table is a quarter turn of 90°, and to accomplish this the pinion, 15, is made with one-fourth the number of teeth of the gear, 14. The gears, 12 and 13, really constitute a single gear in operation, being made in two parts only for convenience in manufacture but being secured rigidly together so as to rotate together. This combination forms a mutilated gear having the same number of teeth as the pinion, 15, and this

mutilated gear is connected for rotation with the worm wheel, 11, by means of dowel pins, 17. But as the rotation of the worm gear, 11, brings the teeth of the gears, 12 and 13, into mesh with the teeth of the pinion, 15, said pinion will be given one complete revolution, and this movement transmitted to the gear, 14, will result in a quarter revolution of said gear and of the table, 3, connected therewith. Beyond its toothed portion the gear 13, is a plain circular plate of the diameter of the gear, 14, minus its teeth, that is, of the diameter of its dedendum circle, so that after its teeth 15 have caused the one complete revolution of the pinion, 15, its circular portion will just pass clear of the teeth of the pinion, 15, allowing it to remain at rest for three-quarters of the revolution of the gear, 13. 20 The gear, 12, is similar to the gear, 13, except that its circular portion, that is, three-quarters of its periphery, coincides with the addendum circle of its teeth; in other words, it is a circular plate, having a series of 25 notches cut in one quarter of its periphery equal in number to the teeth of the pinion, 15, and arranged to register with the spaces between the teeth of the gear, 13. To accommodate the plain circular portion of the 30 gear member, 12, the pinion, 15, is notched at 15^a, such notch being circular in form to fit closely the circular outline of the member, 12, thus preventing the pinion, 15, from rotating while its notch, 15^a, is in registration 35 with the circular portion, 12^a, of the member, 12, but in no wise interfering with rotation of the pinion, 15, when the teeth of the gear members, 12 and 13, are in registration and engage with the teeth of the 40 pinion, 15. The result is that as the power shaft, 9, is continuously rotated driving the worm gear, 11, through the worm, 10, each complete rotation of said worm gear, 11, causes a quarter turn of the gear, 14, and 45 the carrier table, 3, associated therewith; but such quarter turn of the table, 3, takes place at the same speed as the rotation of the worm gear, 11, and the table, 3, remains stationary for the succeeding three-quarters 50 of the revolution of the worm gear, 11, being in fact locked against rotation by the engagement of the notch, 15^a, with the blank circular portion, 12^a, of the member, 12, as above described. 55 Because of possible backlash, however, in the gears of the Geneva stop combination this gearing is not to be relied upon to stop the carrier, 3, with the dies, 2, accurately registered with the discharge nozzle, 4, of the 60 melting pot, 1; the periphery of the table, 3, is therefore provided with a series of short abutments, 18, one for each set of dies on the carrier, and each adapted to engage a corresponding abutment, 19, on the melting 65 pot as the die comes to registering position.

It should be explained that the melting pot, 1, is mounted for limited reciprocation upon guide rods, 20, such reciprocation being effected by means of a follower, 21, engaging a cam, 22, which is continuously rotated by its cam shaft, 23, having a worm gear, 24, meshing with a worm, 25, on the shaft, 9. In what may be called its normal position the abutment, 19, of the melting pot, 1, extends in the path of the abutment, 18. Just prior to the discharge of molten metal from the melting pot, 1, into the die, 2, the cam, 22, causes the melting pot, 1, to move toward the die, 2, for close engagement of its nozzle, 4, with the inlet opening of the die. 70 Just after the discharge of metal has been completed the cam, 22, causes the melting pot to move back away from the die, 2, sufficiently to entirely disengage its abutment, 19, from the abutment, 18, and this occurring just as the teeth of the gears, 12 and 13, come into mesh with the teeth of the pinion, 15, permits the carrier table, 3, to make its next quarter-turn movement to bring the next die into registration with the 75 nozzle, 4, on the melting pot, 1. During this movement the cam, 22, returns the melting pot and its abutment, 19, to normal position ready to engage the next abutment, 18, and 80 interrupt rotation of the carrier table, 3, at 85 the proper point. It will be seen that these movements can be very accurately related by reason of the positive gear connection of both the melting pot, 1, and the rotary carrier, 3, with the same power shaft, 9. 90

It should be explained that strictly speaking the cam, 22, does not effect the movement of the melting pot, 1, but permits such movement under the influence of heavy compression springs, 26, shown in Figs. 1 and 2. The pressure of these springs against the rotary table, 3, is absorbed by a roller, 27, carried on a bracket, 28, in position to engage segmental finished surfaces, 3^b, of a flange, 3^c, formed on the underside of the 100 table, 3. 105

The interior construction of the melting pot, 1, may be substantially similar to that shown in my application Serial No. 62524, which includes an approximately U-shaped 110 conduit somewhat resembling a hollow crank shaft whose hollow trunnions communicate respectively with the discharge nozzle, 4, and the compressed air pipe, 29, while the portion of the conduit offset from said trunnions is formed with an intake port through which it may receive the molten metal when said port is submerged therein in the melting pot, 1. As more fully described in my 115 said application this U-shaped conduit is 120 rotated through a limited angle on its trunnions for closing its intake port against a valve whose stem is seen at 30, on Fig. 1. Such movement of the conduit is effected 125 by a bell crank, 31, connected yieldingly to 130

a link, 32, through a spring, 33, and operated by a follower, 34, engaging a cam, 35, on the cam shaft, 23, already mentioned. It may be understood that the link, 32, reaches 5 down into the melting pot for connection with the offset portion of the U-shaped conduit therein, so that upward movement of the horizontal arm of the bell crank, 31, swings up the ported portion of the conduit 10 for closing of its port by the valve whose stem, 30, appears in Fig. 1; and a slight further movement of the bell crank, 31, which is permitted by the yielding spring connection, 33, with the link, 32, causes its 15 third arm, 31^a, to depress the valve plunger, 36, of the air valve, 37, to admit compressed air to one end of the conduit within the melting pot, 1, whereby the contents of the conduit is forcibly discharged into the die, 2, waiting to receive it. It may be understood that the quantity of molten metal thus 20 temporarily isolated in the U-shaped movable conduit in the melting pot, 1, will be ample for filling the mold of the die, 2. It 25 will also be seen that since the operations just described are controlled by the cam, 35, on the same shaft, 23, which carries the cam, 22, such operations will be properly timed to occur while the nozzle, 4, is closely and 30 forcibly engaged with the intake mouth of the die, 2.

The full capacity of this machine is four dies but the presence of four dies is not necessary to the operation of the machine; 35 it may be used, if desired, with only one, two or three dies. When one or more dies is omitted, however, it is necessary to prevent the discharge of molten metal from the nozzle, 4, at times when there are no 40 dies present to receive it. For this purpose the air supply pipe, 38, leading to the valve, 37, is provided with a second valve, 39, whose plunger, 40, is positioned for actuation by cam abutments, 41, removably applied to 45 the outer surface of the flange, 3^c, of the table, 3. One of these cam abutments, 41, is positioned on the flange, 3^c, directly below each of the dies, 2, carried on the table, 3, so that as each die comes into registration 50 with the nozzle, 4, the cam, 41, depresses the plunger, 40, and opens the air valve, 39, admitting air under pressure as far as the valve, 37. If one of the dies is removed from the table, 3; however, its corresponding cam 55 abutment, 41, is removed from the flange, 3^c, so that when the table, 3 stops at the position at which the removed die, 2, would otherwise engage the nozzle, 4, the valve, 39, is not opened, and although the bell crank, 31, 60 goes through its regular movement, including even the operation of the valve, 37, no metal is discharged through the nozzle, 4, because the compressed air is held in check at the valve, 39. This simple expedient of 65 removing the cam member, 41, when its cor-

responding die, 2, is removed thus makes it possible to operate the machine at less than full capacity whenever it is desired to do so.

As previously mentioned, the upper half, 7^a, of each die is carried by a cross head, 7, mounted to reciprocate vertically upon the guide rods, 6, which connect the table, 3, with the head plate, 5. The cross head, 7, includes a threaded stem, 7^a, permitting accurate adjustment to various sizes of dies, such stem, 7^a, being connected by links, 42, with crank pins, 43, carried by the flanges, 44, formed at either end of the spur gear, 45, which is journaled in brackets, 46, hung 80 from the head plate, 5. Connecting with each of the spur gears, 45, is a rack, 47, mounted for radial reciprocation on the under side of the head plate, 5, and carrying at its inner end a follower roller, 48, 85 engaging the groove of a cam, 49, which is fixed to the stationary post or column, 8, upon which the head plate, 5, rotates with the carrier table, 3. At its inner limit of reciprocation, as shown in Fig. 3, the rack 90 bar, 47, moves the gear, 45, and its associated crank pins, 43, and links, 42, in position for closing together the two halves, 2^a and 2^b, of the die, 2. The cam groove, 48, is so formed that this position of the die parts 95 is secured while the die is in position for registration with the nozzle, 4, of the melting pot and for receiving the molten metal therefrom. As the carrier rotates to move the die with its casting away from the filling 100 position, the cam groove, 48, causes the rack bar, 47, to travel outward, whereupon the upper die member, 2^a, is raised away from the lower member, 2^b, so that the casting in the mold can be removed. This open relation of the dies is then preferably maintained until just before they return for 105 registration with the nozzle, 4, to receive another casting, thus giving opportunity for an attendant not only to remove the casting 110 but also to clean the dies if necessary before they are refilled, and in some cases to reset core members in the mold or to insert parts of different metal which are to be embodied in the finished casting.

To render the casting removable from the dies as quickly as possible it is chilled by means of cooling water flowing through suitably arranged ducts in the sub-plates or blocks, 2^c, which are secured in contact with their respective members of the die, 2. In the ordinary die casting machine, however, it is very easy to ruin a casting by unskillful management of the cooling water; in the present machine it is the purpose to keep the dies at as nearly a uniform temperature as possible, and to accomplish this the cooling water is so controlled as to flow through the sub-plates, 2^c, only part of the time, and principally during the time when the die is 115 120 125 130

occupied by the hot casting. The cooling water is thus controlled by means of relatively rotating valve members, 50 and 51, mounted on the stationary post, 8, which is hollow and through which the water supply and return pipes, 52 and 53, respectively, extend for communication with the valve members, 50 and 51. As shown in Fig. 3, the upper threaded ends of both pipes, 52 and 53, 10 are screwed into a connecting block, 54, fixed in the hollow post, 8, as by a screw, 55, and having two ducts, 54^a and 54^b, leading respectively to channels, 50^a and 50^b, in the valve member, 50. Supply and return pipes, 15 56 and 57, respectively, connect each of the sub-plates, 2^c, with the outer valve member, 51. As indicated in Fig. 6, the return pipes, 57, simply open to the inner cylindrical surface of the valve member, 51, so that they 20 register with the continuous annular groove, 50^b, of the inner valve member, 50, and thus communicate continuously with the return pipe, 53. Each supply pipe, 56, however, connects with a circumferentially extended 25 mouth in the valve member, 51, occupying about 15° of its inner circle, while the groove, 50^a, in the inner valve member extends over about 60° in circumferential direction. Thus it will be seen that each of 30 the supply pipes, 56, is in temporary communication with the supply pipe, 52, during about 90° of the rotary travel of the die, 2, to which said supply pipe, 56, leads. This is of course the 90° of travel in the vicinity of 35 the nozzle, 4, on the melting pot, 1, and the valve members, 50 and 51, may be so adjusted that the water will begin to flow through the sub-plates, 2^c, of the die members just as said die members are closed together and come into registration with the nozzle, 4, such flow being continued and maintained during the filling of the dies with the molten metal, and until they are rotated out of registration with the nozzle, 4, 45 and opened to permit removal of the casting.

Fig. 9 illustrates a modified construction in which the table indicated at 3^x is made to serve the purpose of the cam, 22, and follower, 21, shown in Fig. 1, and previously described. The table, 3^x, is formed with a rim having cam notches, 3^y, corresponding in number to the number of dies to be carried by the table and adapted to coöperate 50 with a roller, 1^y, mounted upon the end of the melting pot, 1^x. The melting pot, 1^x, is mounted as in the principal construction, upon guide rods, 20, provided with compression springs, 26, tending to force the 55 melting pot, 1^x, toward the table, 3^x, for connection of its nozzle, 4^x, with the inlet of one of the dies on the table. The concentric portions of the rim of the table which occur 60 between successive notches, 3^y, will serve by 65 coöperation with the roller, 1^y, to hold the

melting pot, 1^x, and its nozzle, 4^x, away from the table, 3^x, until one of the notches, 3^y, is rotated by the table movement into registration with the roller, 1^y, to permit the advance of the melting pot, 1^x, under pressure 70 of the springs, 26. The notch, 3^y, may be deep enough in relation to the size of the roller, 1^y, to serve also as a centering means for quite accurately relating the rotary table, 3^x, to the nozzle, 4^x, of the melting pot, 75 said table being driven by the Geneva stop gearing described in connection with the principal construction shown in Fig. 1. Thus it may be understood that while the cam shaft, 23, and its cam, 35, may still be required to actuate the internal parts of the melting pot, 1^x, in a manner already described, the reciprocation of the melting pot will be provided for by a rather simpler mechanism. 80

Fig. 9, together with Figs. 10 and 11, also shows means for cleaning the face of the nozzle, 4^x, after each discharge therefrom to insure better connection between said nozzle and the next die to which it is to deliver 90 the molten metal. Such means consists of a rotary brush, 58, carried on a vertical spindle, 59, journaled in the table, 3^x, and partially shown in preceding views in a position intermediate of each two dies thereon. 95 Thus for the particular machine shown, there are four brushes, 58. Mounted on the melting pot for movement therewith is a plate, 60, formed with a segmental gear, 61, which will be positioned to mesh with a pinion, 62, on the spindle, 59, as said spindle traverses the arc occupied by this gear segment, 61, in the rotation of the table by which one die is moved out of registration with the nozzle and the next die moved into such 105 registration. The gear segment, 61, being positioned within the angle of rotation within which the nozzle of the melting pot is included, it will be evident that each of the brushes, 58, will be rapidly rotated as it 110 passes the nozzle, thereby cleaning the latter of any solidified particles of the metal which may have been deposited thereon in the last preceding casting operation. Preferably, as will be seen by reference to the 115 arrow, A, indicating the direction of rotation of the table, the brushes, 58, are arranged to rotate so that their peripheral travel against the nozzle is in the direction opposite to that of the table, thus securing 120 the maximum brushing effect.

Fig. 12 illustrates a modified form of control for the air valve, 37, to prevent effective actuation of said valve when one set of dies is omitted from the table, 3. The third arm, 31^a, of the bell crank, 31, connects yielding instead of positively with the valve lever, 36, through a compression spring, 63, and the lever is formed with a stop shoulder, 36^a, in whose path may be interposed the 130

end of a push rod, 64. According to this modification the flange, 3^c, of the table, 3, normally carries no cam blocks like those shown at 41, in Fig. 1, but when one of the dies is omitted from the table a cam block, 65, similar to the block, 41, is attached to the flange, 3^c, and as the table rotates said block, 65, forces the push rod, 64, into the position shown in Fig. 12, so that when the bell crank, 31, moves it can only compress the spring, 63, and will not actuate the valve lever, 36. It will be understood that when the block, 65, is absent a retracting spring, 66, removes the rod, 64, from the path of the shoulder, 36^a, and the compression spring, 63, being much stronger than the retracting spring, 67, the valve lever is actuated to open the valve, 37, and admit air to the melting pot in the usual manner.

20 I claim:—

1. The combination of a melting pot, a discharge nozzle therefor, a plurality of dies or molds each adapted for connection with the discharge nozzle, a rotary carrier on which said dies are mounted symmetrically about the axis of rotation, and means for imparting automatically intermittent rotation to said carrier for moving such dies successively into and out of registration with

25 said nozzle.

2. The combination of a melting pot, a discharge nozzle therefor, a plurality of dies or molds each adapted for connection with the discharge nozzle, a rotary carrier on which said dies are symmetrically disposed with respect to the axis of rotation, a power member, and gearing including a Geneva stop motion operatively connecting said power member with said rotary carrier for 30 imparting intermittent rotation to the carrier to move the dies successively into and out of registration with said nozzle.

3. The combination of a melting pot, a discharge nozzle therefor, a plurality of dies or molds each adapted for connection with the discharge nozzle, a rotary carrier upon which said dies are arranged symmetrically about the axis of rotation, a power member, gearing including a Geneva stop motion connecting said power member with said rotary carrier for imparting intermittent rotation thereto to move said dies successively into and out of registration with the nozzle, together with a positive stop device positioned 35 to arrest the carrier at positions for accurate registration of said dies with the nozzle.

4. The combination of a melting pot having a discharge nozzle and means for forcing molten metal therefrom under pressure, a plurality of dies or molds each adapted for connection with such discharge nozzle, a rotary carrier upon which said dies are disposed symmetrically about the axis of rotation, a power shaft and gearing connecting said shaft with said carrier adapted for im-

parting intermittent rotation to the latter for moving the dies successively into and out of registration with said nozzle control devices for such metal discharging means, and actuating mechanism for said control devices also geared to said power shaft whereby the rotary adjustment of the carrier and the discharge of the metal from the melting pot are automatically timed with relation to each other.

5. The combination of a melting pot having a discharge nozzle, a plurality of dies or molds each adapted for connection with said discharge nozzle, a rotary carrier upon which said dies are mounted symmetrically about the axis of rotation, means for intermittently rotating said carrier for moving the dies successively into and out of registration with the said nozzle, means for intermittently reciprocating said melting pot 85 for moving the nozzle into and out of contact with said dies, said carrier having a series of abutments corresponding respectively to the dies on the carrier, and said melting pot having a co-operating abutment 90 normally positioned to arrest the rotation of the carrier for effecting accurate registration of the nozzle with one of the dies, the abutment on the melting pot being dimensioned to withdraw from the engagement with the 95 abutment on the carrier when said melting pot is reciprocated in direction or separating the nozzle from the die.

6. The combination of a melting pot having a discharge nozzle, a supply of compressed air for discharging molten metal therefrom under pressure, a valve controlling said compressed air supply, a plurality of dies or molds each adapted for connection with such discharge nozzle, a carrier on 100 which said dies are mounted adapted for moving them successively into and out of registration with said nozzle, and means removably and replaceably mounted on the die carrier at angular intervals about its 105 axis, corresponding to the angular intervals between the dies thereon for controlling the openings of the air-supply controlling valve in accordance with the number of dies which are present on the carrier.

7. The combination of a melting pot having a discharge nozzle, a supply of compressed air for discharging molten metal therefrom under pressure, a plurality of dies or molds each adapted for connection 110 with such discharge nozzle, a rotary carrier upon which said dies are disposed symmetrically about the axis of rotation, means for imparting intermittent rotation to the carrier for moving such dies successively 115 into and out of registration with said nozzle, a valve controlling the compressed air supply, and a plurality of cam abutments removably mounted on the carrier in proper relation to the respective dies thereon for 120

controlling the opening of said air valve in accordance with the dies present on the carrier.

8. The combination of a melting pot, a discharge nozzle therefor, a plurality of dies or molds each adapted for connection with the discharge nozzle, a carrier for said dies mounted for moving them successively into and out of registration with said nozzle, 10 said dies being provided with ducts for cooling fluid, and a valve device operated by the movement of the carrier and controlling the admission of cooling fluid to said ducts of the dies, said valve device being adapted 15 to permit circulation of the cooling fluid in such ducts of each die only while the die remains in the vicinity of the said discharge nozzle of the melting pot.

9. The combination of a melting pot having a discharge nozzle, a plurality of dies or molds each adapted for connection with such discharge nozzle, a rotary carrier on which said dies are mounted symmetrically about the axis of rotation, each of said dies 20 being formed with ducts adapted to receive cooling fluid, a hollow stationary post upon which the carrier is mounted for rotation, supply and return pipes for cooling fluid disposed in said post, the post having ports 25 communicating with said pipes respectively, an annular valve member connected to the carrier for rotation therewith around the ported portion of the post, said valve member having ports corresponding respectively 30 to the dies on the carrier and parts connecting said ports with their respective dies, such ports in the valve being positioned for registration with the corresponding ports 35 of the post whereby the rotation of the carrier controls the supply of cooling fluid to the dies.

10. The combination of a melting pot having a discharge nozzle, a plurality of two-part dies or molds each adapted for connection with the discharge nozzle, a rotary carrier on which said dies are mounted, and means for imparting intermittent rotation to said carrier for moving said dies successively into and out of registration with said 45 nozzle, together with means on the carrier for supporting one part of each die independently of the other part, and mechanism for reciprocating such supporting means for separating or closing together the 50 two parts of the die, such mechanism including actuating means controlled by the rotation of the carrier adapted for closing and holding closed the two parts of each die while such die is in the vicinity of the 55 discharge nozzle, and adapted to cause separation of the two parts of such die when the latter is removed from the discharge nozzle by rotation of the carrier.

11. The combination of a melting pot, a 60 discharge nozzle therefor, a plurality of dies

or molds each adapted for connection with the discharge nozzle, and a carrier for said dies mounted for moving them successively into and out of registration with said nozzle, together with a brush on the carrier positioned between successive dies thereon and adapted to wipe the end of the nozzle after disengagement of one die and before engagement of the next die therewith. 70

12. The combination of a melting pot, a discharge nozzle therefor, a plurality of dies or molds each adapted for connection with the discharge nozzle, and a carrier for said dies mounted for moving them successively into and out of registration with said nozzle, 75 together with a rotary brush on the carrier positioned to wipe the nozzle as it travels past the latter when the carrier moves, and means for rotating the brush in direction for causing peripheral travel thereof against the 80 nozzle opposite the direction of movement of the carrier.

13. The combination of a melting pot, a discharge nozzle therefor, a plurality of dies or molds each adapted for connection with the discharge nozzle, a rotary carrier on which said dies are mounted symmetrically about the axis of rotation, and means for imparting intermittent rotation to said carrier for moving such dies successively into 90 and out of registration with said nozzle, together with a rotary brush journaled on the carrier between successive dies and positioned to wipe the discharge nozzle, a gear on said brush, and a gear segment carried 95 by the melting pot in position to mesh with said gear as the rotation of the carrier moves the brush past the discharge nozzle. 100

14. The combination of a melting pot, a discharge nozzle therefor, a plurality of dies or molds each adapted for connection with the discharge nozzle, a rotary carrier upon which said dies are arranged symmetrically about the axis of rotation, a power member, gearing including a Geneva stop motion connecting said power member with said rotary carrier for imparting intermittent rotation thereto to move said dies successively into and out of registration with the nozzle, together with centering means carried by said 110 melting pot, and adapted for arresting the carrier at positions for accurate registration of its dies with the nozzle. 115

15. The combination of a melting pot, a discharge nozzle therefor, a plurality of dies or molds each adapted for connection with the discharge nozzle, a rotary carrier upon which said dies are arranged symmetrically about the axis of rotation, a power member, gearing including a Geneva stop motion connecting said power member with said rotary carrier for imparting intermittent rotation thereto to move said dies successively into and out of registration with the nozzle, guides on which the melting pot is mounted 120 125 130

- for reciprocation toward and from the axis of the carrier, compression springs tending to move the melting pot toward the carrier, said carrier including a notched circular member, and a follower on the melting pot adapted to engage said circular member whereby the melting pot is permitted to advance toward the carrier when the follower engages a notch of said circular member.
16. The combination of a melting pot having a discharge nozzle, a supply of compressed air for discharging molten metal therefrom under pressure, a valve controlling said compressed air supply, a plurality of dies or molds each adapted for connec-

tion with such discharge nozzle, a carrier on which said dies are mounted adapted for moving them successively into and out of registration with said nozzle, a locking device normally inoperative but adapted to prevent the opening of said valve, and actuating means for said lock adapted to be demountably secured to the carrier when one or more of the dies is omitted therefrom for preventing opening of the air valve in the absence of such dies.

In testimony whereof I have hereunto set my hand at New York city, N. Y., this 3d day of January, 1916.

JOHN K. STEWART.
